UNITED STATES PATENT OFFICE

163,947

HAND TRAP

Carl J. Gulde, St. Joseph, Mo.

Application January 5, 1950, Serial No. 7,015

Term of patent 3½ years

(Cl. D34—5)

To all whom it may concern:

Be it known that I, Carl J. Gulde, a citizen or the United States of America, residing at St. Joseph, in the county of Buchanan, and State of Missouri, have invented a new, original, and ornamental Design for a Hand Trap, of which the following is a specification, reference being had to the accompanying drawing, forming a part thereof.

In the drawing:

Fig. 1 is a top plan view of a hand trap, showing my new design;

Fig. 2 is an enlarged fragmentary side elevational view thereof; and

Fig. 3 is an enlarged fragmentary side elevational view thereof, with the elastic member removed therefrom.

The handle, which is of uniform thickness

throughout, has been partially broken away in Figs. 2 and 3 for convenience of illustration. The bottom of the hand trap has substantially the same appearance as that shown in Fig. 1.

I claim:

The ornamental design for a hand trap, as shown and described.

CARL J. GULDE.
